UNITED STATES PATENT OFFICE.

WALTER E. GASKILL, OF PRINCETON, NEW JERSEY, ASSIGNOR TO MERGENTHALER LINOTYPE COMPANY, A CORPORATION OF NEW YORK.

TYPOGRAPHICAL MACHINE.

1,182,555.

Specification of Letters Patent.

Patented May 9, 1916.

Application filed February 23, 1915. Serial No. 9,874.

To all whom it may concern:

Be it known that I, WALTER E. GASKILL, a citizen of the United States, residing at Princeton, in the county of Mercer and State 5 of New Jersey, have invented certain new and useful Improvements in Typographical Machines, of which the following is a specification, reference being had therein to the accompanying drawing.

10 My invention relates to typographical composing machines, such as linotype machines of the general organization represented in Letters Patent of the United States, No. 426,532, to O. Mergenthaler, wherein circulating matrices are released from a magazine or magazines in the order in which their characters are to appear in print and then assembled in line, the composed line transferred to the face of a mold, the mold filled with molten metal to 15 form a slug or linotype against the matrices which produce the type characters thereon, and the matrices thereafter elevated and returned through a distributing mechanism to the magazine or magazines from which 20 they started. These machines are frequently equipped with a so-called font-distinguisher, which is located in advance of the distributing mechanism and serves to prevent the delivery thereto of matrices of improper font, 25 that is, matrices of a font different from that contained in the particular magazine in use. Ordinarily, the matrices are formed in their lower ends with notches which are 30 differently positioned in the respective fonts, so that only those of a certain font or those 35 having notches in a given location can pass the font-distinguisher, while those of other forms or fonts are arrested thereby.

Heretofore in practice, the various fonts 40 of matrices have been distinguished from each other merely in respect to size or what is technically known as "point," so that if two or more fonts of matrices were of different style or face but of the same point, it 45 would be possible for them to pass the font-distinguisher and be distributed into the same magazine, thereby resulting in a mixture of faces and with substantially the same annoyance and objections as are present 50 in connection with a mixture of sizes.

It is the object of my present invention to prevent this liability, and to that end I employ several font-distinguishers which serve not only to prevent the delivery to the distributing mechanism of matrices of improper 55

size or point, but also of matrices of improper style or face.

In the accompanying drawings, I have shown my improvement in preferred form and by way of example and as applied to a 60 linotype machine of the usual construction, but obviously it is capable of broader application, and may be embodied in other forms and applied to other styles of typographical machines, such for instance as type setters, 65 and the like, and still be comprised within the spirit of my invention. Generally speaking, I desire it to be understood that I do not limit myself to any specific form or embodiment, except in so far as such limitations 70 are specified in the claims.

Referring to the drawings: Figure 1 is a front view of a portion of a linotype machine having my invention applied thereto; Fig. 2 is a section on the line 2-2 of Fig. 75 1; Fig. 3 is a section on the line 3-3 of Fig. 1; Fig. 4 is a section on the line 4-4 of Fig. 1; and Figs. 5, 6 and 7 are diagrammatic views showing the manner in which matrices of various fonts are distinguished 80 from each other in form.

In the accompanying drawings, I have shown my invention as embodied in a machine equipped with a plurality of magazines, and of the class illustrated in United 85 States Letters Patent No. 1,109,872, to John R. Rogers. In the present instance, only two magazines A¹, A² are shown, although of course a greater number could be employed. These magazines are mounted in 90 the shift frame A, which can be moved up and down to bring one or another of the magazines into operative relation to the channel entrance B, into which the matrices are delivered by the distributing mechanism 95 C. Located in advance of the distributing mechanism is the distributor box D, through which the matrices are transferred by the pusher E, the matrices being delivered therefrom, one at a time, to the distributing mechanism by the lifting finger F, all in the usual way.

According to my present invention, I provide each matrix with a point-distinguishing notch X¹ and two face-distinguishing notches X² and X³ respectively. The notch X¹ is formed in one of the vertical edges of the matrix and is located in different vertical positions in fonts of different point. For instance, Fig. 7 shows diagrammatically 105 110

eight different positions of the notch X^1 for as many different fonts which vary as to point. The face-distinguishing notch X^2 is formed in the same edge of the matrix and varies in depth according to a given unit in fonts differing as to face. For instance, in Fig. 5 nine different depths of notch are indicated for as many different fonts of unlike face. In order to distinguish a still greater number of fonts, this notch X^2 may also be located in different vertical positions along the edge of the matrix. For example, Fig. 6 indicates eight different vertical positions for the notch, in each of which positions the notch may also vary as to depth. It follows, therefore, that the vertical position of the notch X^2 will be the same for a group of nine different fonts, and that its varying depths will serve to distinguish these fonts from one another in the group. The other face-distinguishing notch X^3 is formed in the bottom of the matrix and is located in different horizontal positions in fonts of unlike face, Fig. 5 showing nine different positions of the notch. It is to be observed at this time that the notch X^3 bears a special relation to the notch X^2 , the depth of the latter controlling the location of the former. In other words, any variation in the depth of the notch X^2 will be accompanied by a corresponding difference in location of the notch X^3 . The purpose of this will later be pointed out.

To coöperate with the matrices of the special forms above noted, I provide three font-distinguishers x^1 , x^2 , and x^3 . These may be located in any convenient part of the machine, but I prefer to mount them in the distributor box D. The distinguisher x^1 is associated with the point-distinguishing notch X^1 and is adjustable vertically to correspond to the different locations of the notch in different fonts. The distinguisher x^2 is associated with the face-distinguishing notch X^2 and is arranged so as to be adjustable vertically and horizontally to correspond both to the different positions and the varying depths of the notch in the different fonts. The distinguisher x^3 is associated with the face-distinguishing notch X^3 and is adjustable laterally to correspond to the different locations of the notch.

The distinguisher x^3 is intended to supplement the distinguisher x^2 , as the latter is inadequate in certain conditions. For instance, if the distinguisher x^2 be set in position to correspond to a notch X^2 of any given depth, then matrices having a greater depth of notch would be allowed to pass the distinguisher and be distributed into an improper magazine. The employment of the distinguisher x^3 avoids this liability, as the notch X^3 of the matrices must also register with the distinguisher x^3 before

they can pass thereby. In this connection, it will be remembered that the position of the notch X^3 is dependent upon the depth of the notch X^2 , so that it will have as many different positions as the notch X^2 has different depths. It follows, therefore, that even if the depth of a notch X^2 were such as to allow an improper matrix to pass the distinguisher x^2 , the position of the notch X^3 would not permit it to pass the distinguisher x^3 .

The adjustments of the several font-distinguishers may be effected in any desired manner—manually or otherwise. In the present instance, I have shown means for effecting their adjustments automatically, these means being controlled in their action by the movement of the magazines, in such manner that when any selected magazine is brought into operative position, the several font-distinguishers will be properly adjusted to correspond to the particular style and size of the matrices therein contained. Referring to Fig. 3, it will be noted that the point-distinguisher x^1 is attached to the end of a small plunger G, which is movable vertically within a cylindrical casing G^1 attached to the side of the distributor box, a spring G^2 being interposed between the casing and plunger and tending normally to push the latter downward to its lowermost position. The downward movement of the plunger G is resisted or controlled by an arm G^3 connected to one end of a transverse rock shaft G^4 mounted in suitable bearings on the framework, the opposite end of the rock shaft (Fig. 1) being provided with a crank arm G^5 which is connected to an upright lever G^6 . Similarly (Fig. 4) the face-distinguisher x^2 is attached to a plunger H movable vertically within a casing H^1 , a spring H^2 being interposed between the casing and plunger and tending normally to push the latter downward to its lowermost position. This downward movement of the plunger H is resisted or controlled by an arm H^4 connected to one end of a rock shaft H^5 , journaled in suitable bearings in the framework and provided at its outer end (Figs. 1 and 2) with a crank arm H^6 which is connected to a second upright lever H^7 . In order that the distinguisher x^2 may also be adjusted laterally, to vary its extent of projection into the distributor box to correspond to the varying depths of the notch X^2 , the casing H^1 is slidably mounted upon two rods H^8 , projecting laterally from the side of the distributor box and passing through openings in the casing.

The distinguisher x^3 is carried by a stud I adjustably mounted in the under side of the distributor box, a spring I¹ being interposed between the box and stud and tending normally to hold the distinguisher in its

extreme right-hand position in the box. Inasmuch as the position of the distinguisher x^3 should depend upon the extent of projection of the distinguisher x^2 , I 5 provide means for effecting their corresponding adjustments. In the present instance, these means comprise a rocking lever J connected at one end to the stud I and at its opposite end to the casing H^1 . 10 The lever J is fixed to one end of a rock shaft J^1 journaled in suitable bearings in the framework and provided at its opposite end with a crank arm J^2 which is connected to a third upright lever J^3 . 15 The three levers G^6 , J^3 and H^7 are arranged side by side in close order (Fig. 1), all being pivotally mounted at their upper ends upon a common stud K and having their lower ends arranged in position to be 20 engaged by a pair of plates G^7 and J^5 connected to the side edge of a magazine. The plate G^7 , which controls the point-distinguisher x^1 , is of such shape and size, that when the magazine is brought into action, it 25 will rock the lever G^6 so as to cause the distinguisher, through the intermediate connections, to be set in a position corresponding to the notch X^1 of the matrices contained in the magazine. The plate J^5 30 (Fig. 1) which controls both face-distinguishers x^2 and x^3 is provided with two distinct surfaces J^4 and H^8 to engage the levers J^3 and H^7 respectively. The size of the plate or the shape of the two faces is 35 such as to rock the two levers J^3 and H^7 the proper extent to locate their respective distinguishers in position to correspond to the location of the face-distinguishing notches X^2 , X^3 of the matrices in the magazine. It 40 will be remembered in this connection that the lever J^3 controls the horizontal adjustment of both the distinguishers x^2 and x^3 , while the vertical adjustment of the former is controlled by the lever H^7 . 45 It is to be noted that plates G^7 and J^5 are attached to each of the magazines and that their form or size are made to correspond to the particular font of matrices therein contained, both as regards point and 50 face. For instance, the upper magazine in Fig. 3 is shown as provided with a plate G^7 corresponding to a six-point font and a plate J^5 corresponding to an antique No. 4 face; while the lower magazine in this 55 figure is shown as provided with a plate G^7 corresponding to a twelve-point font and a plate J^5 corresponding to an old style No. 2 face. Again, in Fig. 4 is illustrated a plate G^7 corresponding to a six-point font 60 and a plate J^5 corresponding to an old style No. 1 face. The plates G^7 and J^5 are detachably connected to the magazines by screws L so that they may be replaced by others of different sizes or forms corresponding to other fonts. In this way each 65

magazine may contain any font desired, and corresponding plates attached to the magazine.

While I have shown my invention embodied in a machine employing a plurality 70 of magazines, which are movably arranged in the machine so that one or another may be brought into operative position, and while I have shown means whereby the font-distinguishers will be automatically adjusted 75 to correspond to the font contained in the magazine thus brought into action, yet it will be understood that my invention is equally applicable to machines employing a single magazine, wherein the adjustment of 80 the font-distinguishers will be controlled by the substitution of a magazine in that type of machine. Or, as before stated, the adjustment of the font-distinguishers may be effected manually. It will also be understood 85 that the particular embodiment of my invention as herein shown is merely by way of example and may be widely varied by the skilled mechanic without departing from its scope. It will be obvious, of course, 90 that the notches X^2 and X^3 of the matrices might also be used to distinguish fonts of unlike point instead of face, the invention in its broad aspect including all combinations or uses of such notches as are defined 95 by the claims.

Having thus described my invention, its construction and mode of operation, what I claim and desire to secure by Letters Patent of the United States, is as follows: 100

1. In a typographical machine, the combination with a face-distinguisher and a point-distinguisher, of a font of type or matrices each formed with two notches, one adapted to coöperate with the face-distinguisher and the other with the point-distinguisher. 105

2. In a typographical machine, the combination with two font-distinguishers, of a plurality of fonts of type or matrices each formed with two notches to coöperate with the distinguishers, the said notches differing in their relative location in the matrices of the respective fonts. 110

3. In a typographical machine, the combination with a face-distinguisher and a point-distinguisher, of a plurality of fonts of type or matrices each formed with two notches, one adapted to coöperate with the face-distinguisher and the other with the point-distinguisher, the said notches differing in location in the matrices of the respective fonts. 115

4. In a typographical machine, the combination with a point-distinguisher and a face-distinguisher, of a plurality of fonts of type or matrices each formed with two notches, one adapted to coöperate with the point-distinguisher and the other with the face-distinguisher, the former notch differ- 120 125 130

- ing in location and the latter varying in depth in the matrices of the respective fonts.
5. In a typographical machine, the combination with a point-distinguisher and two face-distinguishers, of a plurality of fonts of type or matrices each formed with three notches, one adapted to coöperate with the point-distinguisher and the others with the 5 face-distinguishers, the former notch and one of the latter notches differing in location and the remaining one varying in depth in the matrices of the respective fonts.
6. In a typographical machine, the combination with two font-distinguishers, of a plurality of fonts of type or matrices each formed with two notches to coöperate therewith, one of said notches differing in location and the other varying in depth in the 10 matrices of the respective fonts.
7. In a typographical machine, the combination with two face-distinguishers, of a plurality of fonts of type or matrices each formed with two notches to coöperate therewith, one of said notches differing in location and the other varying in depth in the 15 matrices of the respective fonts.
8. In a typographical machine, the combination with two font-distinguishers, of a plurality of fonts of matrices divided into groups and each formed with two notches to coöperate with the font-distinguishers, one of said notches being located in different positions in the respective groups and the 20 other being located in different positions in the respective fonts of each group.
9. In a typographical machine, the combination with two face-distinguishers, of a plurality of fonts of type or matrices divided into groups irrespective of point and each formed with two notches to coöperate with the face-distinguishers, one of said notches being located in different positions in the respective groups and the other being 25 located in different positions in the respective fonts of each group.
10. In a typographical machine, the combination with a font-distinguisher, of a plurality of fonts of type or matrices divided 30 into groups and each formed with a notch to coöperate with the font-distinguisher, said notch differing in location in the respective groups and varying in depth in the respective fonts of each group.
11. In a typographical machine, the combination of a group or line of type or matrices varying in form both as to face and point, and means to coöperate therewith and detect the presence therein of a matrix 35 of improper face irrespective of point.
12. In a typographical machine, the combination of a group or line of type or matrices varying in form both as to face and point, and means to coöperate therewith and detect the presence therein of a matrix 40 of improper face irrespective of point.
- either of improper face or point, as the case may be.
13. In a typographical machine, two font-distinguishers, each adjustable relatively to the other to different operative positions to correspond to different fonts of type or matrices. 70
14. In a typographical machine, the combination of a point-distinguisher and a face-distinguisher, each of said distinguishers being adjustable to different operative positions to correspond to fonts of type or matrices which differ as to face or point, or both. 75
15. In a typographical machine, the combination of a magazine to contain the type or matrices and adapted to be brought into action at will, two-font distinguishers, each adjustable to different operative positions, and automatic mechanism for adjusting the font-distinguishers when the magazine is brought into action to correspond to the particular font of type or matrices contained therein. 80
16. In a typographical machine, the combination of a magazine to contain the type or matrices, and adapted to be brought into action at will, an adjustable point-distinguisher, and an adjustable face-distinguisher, with automatic mechanism for adjusting said distinguishers when the magazine is brought into action to correspond to the point and face of the particular font of type or matrices contained therein. 85
17. In a typographical machine, the combination of an adjustable point distinguisher and two coöoperating adjustable face-distinguishers, with mechanism for adjusting said distinguishers to correspond to different fonts of type or matrices. 90
18. In a typographical machine, the combination of a point-distinguisher adjustable to different operative positions, and two face-distinguishers, each adjustable independently to different operative positions, 95 for the purpose described. 100
19. In a typographical machine, the combination of a channel through which the type or matrices pass sidewise or laterally, and a font-distinguisher projecting transversely across said channel and adjustable to vary its extent of projection into the path of travel of the type or matrices. 110
20. In a typographical machine, the combination of a channel through which the type or matrices pass, and a font-distinguisher projecting into said channel and adjustable to vary its extent of projection, said distinguisher being further adjustable to different positions within the channel irrespective of its extent of projection. 115
21. In a typographical machine, the combination of a channel through which the type or matrices pass, a font-distinguisher projecting into said channel and adjustable 120
- 65

to vary its extent of projection, and a second distinguisher also located in the channel and adjustable to different operative positions therein to correspond to the extent of projection of the first, for the purpose described.

22. In a typographical machine, the combination of a channel through which the type or matrices pass, a font-distinguisher located therein, means for adjusting said distinguisher to different operative positions, means for projecting it to different extents into said channel in any of its different positions, a second distinguisher located in the channel, and means for adjusting it to different positions therein to correspond to the extent of projection of the first distinguisher in any of its different operative positions, for the purpose described.

23. In a typographical machine, two font distinguishers, one adjustable to different positions to correspond to different groups of fonts of type or matrices, and the other adjustable to different positions to correspond to different fonts in each of said groups.

24. In a typographical machine, the combination of a point-distinguisher adjustable to different operative positions to correspond to different fonts of type or matrices of unlike point, with two face-distinguishers, one adjustable to different positions to correspond to different groups of fonts of type or matrices of unlike face irrespective of point, and the other adjustable to dif-

ferent positions to correspond to the different faces in the several fonts of each group, for the purpose described.

25. A magazine for typographical machines provided with a point-distinguisher controlling plate and a face-distinguisher controlling plate, the said plates corresponding to the particular point and face of the font contained in the magazine.

26. In a typographical machine comprising matrices each formed with a face-distinguishing notch and a point-distinguishing notch, the combination of a channel through which the type or matrices pass, and two font-distinguishers located in said channel in position to engage in the notches of the matrices as they pass therethrough, and adapted to arrest matrices of unlike form.

27. In a typographical machine comprising type or matrices each formed with a point-distinguishing notch and also two face-distinguishing notches, the combination of a channel through which the matrices pass, and three distinguishers located in said channel in position to engage in the notches of the type or matrices as they pass therethrough and adapted to arrest those of unlike form.

In testimony whereof, I have affixed my signature in presence of two witnesses.

WALTER E. GASKILL.
